UNITED STATES PATENT OFFICE.

ARTHUR C. DAVIDSON, OF CHICAGO, ILLINOIS, ASSIGNOR TO WAUGH DRAFT GEAR COMPANY, OF CHICAGO, ILLINOIS, A CORPORATION OF ILLINOIS.

STUB BUFFING-GEAR.

1,248,628.

Specification of Letters Patent.

Patented Dec. 4, 1917.

Application filed July 21, 1915. Serial No. 41,040.

To all whom it may concern:

Be it known that I, ARTHUR C. DAVIDSON, a citizen of the United States, and a resident of the city of Chicago, in the county of 5 Cook and State of Illinois, have invented certain new and useful Improvements in Stub Buffing-Gears; and I do hereby declare that the following is a full, clear, and exact description of the same, reference being had 10 to the accompanying drawings, and to the numerals of reference marked thereon, which form a part of this specification.

Platform gears are generally associated with passenger cars to take up buffing 15 stresses, but in some types of cars, such as blind baggage, refrigerator, or express cars, it has been found difficult, if not impossible, to adapt a conventional form of platform gear to the car. This invention relates to 20 an improved type of buffing gear known as a stub buffer, adaptable for attachment upon cars with which the usual type of platform buffing gear cannot be readily associated, and embodying simplified features of construction which permit connection of the 25 gear to a car without alteration thereof.

It is an object therefore of this invention to construct a buffing gear adaptable to cars without necessitating alterations in the 30 structure thereof, and designed particularly for connection upon those types of cars not provided with platforms.

It is also an object of this invention to construct a stub buffer embracing a combination of shock absorbing mechanisms to 35 absorb both light and heavy impacts imparted thereto.

It is furthermore an important object of this invention to construct a buffing gear 40 embracing a casing adapted to be attached upon a car and to receive engaged therein mechanisms guided by means which are attached to the casing after said mechanisms are put in place, said mechanisms co-acting 45 with other elements associated with the buffer plate to absorb impacts.

It is finally an object of this invention to construct a device simple in operation and construction, and capable of ready attachment 50 to a car.

The invention (in a preferred form) is illustrated in the drawings and hereinafter more fully described.

In the drawings:

Figure 1 is a fragmentary top plan view 55 partly broken away and shown in section, of a buffing gear embracing the principles of my invention.

Fig. 2 is a section taken on line 2—2 of Fig. 1, with parts shown in elevation. 60

Fig. 3 is a central section taken on line 3—3 of Fig. 1, with parts omitted and parts shown in section.

Fig. 4 is a detail section with parts omitted taken on line 4—4 of Fig. 1. 65

As shown in the drawings:

The reference numeral 1, indicates as a whole the end sill of a car, to which is bolted a single heavy casting having a top wall 2, a bottom wall 3, side walls 4, relatively short in length and turned outwardly as shown in Fig. 1, and denoted by the reference numeral 5, and with a number of reinforcing ribs 6, integral with the top wall and the inner or back wall 7, of the casting. 70 At the forward outer ends of said casting, as clearly shown in Figs. 1 and 2, tubular members 8, are formed, being integrally connected to said top and bottom walls 2 and 3, respectively, by webs or ribs 9. Formed 80 upon the under surface of said top wall 2, as clearly shown in Fig. 2, are parallel retaining ribs 10, and formed upon the upper surface of the bottom wall 3, as shown in Figs. 1 and 2, are similarly disposed retaining ribs 11. The purpose of said retaining ribs 10 and 11, is to permit insertion between the top and bottom walls 2 and 3, of the casting, guide elements 12, abutting said ribs and secured to said top and bottom walls 85 2 and 3, respectively, by bolts 13, extending entirely therethrough. The guide elements are not inserted into place within the casting until a movable abutment member or slide- 90 able casing comprising a convex abutment head 14, and a hollow rectangular extension or shank 15, integral therewith, has first been placed within the casing, together with a group of friction plates 16, which seat 95 between the walls 4, over a concave surface 17, formed in the back wall of the casting, and disposed behind said abutment head 14.

As clearly shown in Figs. 2 and 3, the rear wall 7, of the casting is extended downwardly and together with side walls 18, and 105 slotted front wall 19, affords a rigid connec-

tion for an integral bottom plate 20, to which is attached in the manner shown in Fig. 2, a heavy yoke 21, by means of bolts 22. The purpose of said yoke 21, is to support an element 23, which may be a simple drawbar attached on the car, or a combination drawbar and draft gear, but since the details of construction of which form no part of this invention, the same are omitted. The movable member or buffing plate of the gear which receives the direct impact, consists of a heavy cast plate 24, which, on its interior surface, as clearly shown in Fig. 4, is reinforced by a number of ribs and along its upper portion has formed integral therewith a rearwardly extending plate 25, which overlaps the top wall plate 2, of the main casting, having sliding engagement therewith. A circular rib 26, is formed on the inner surface of said abutment plate 24 and engaged therearound and seating against the rear wall of said plate is a heavy coiled spring 27, which also fits into the hollow rectangular extension 15, of the convex follower element 14, hereinbefore described.

Rectangular shaped recesses 28, are provided near each end on the inner side of said abutment plate 24, each having a centrally disposed groove 29, and cover plates 30, are provided, adapted to be secured over said recesses by means of rivets 31. Each of said cover plates 30, as clearly shown in Figs. 1 and 4, is likewise deformed, as indicated by the reference numeral 32, to form a groove on its inner surface to register with the groove 29, thus affording substantially a cylindrical recess within which may seat a cylindrical member 33, inserted through and secured within the apertured end of a guide bar 34, thus permitting a certain amount of pivotal movement of said guide bar with respect to the abutment plate 24, due to such connection. Said guide bars 34, extend through the tubular elements 8, of the main casting, and also through apertures provided in the extension walls 5, and each bar at its end, is provided with a cotter pin 35, therethrough, to limit the outward movement thereof.

Coiled about each of said guide bars 34, is a relatively heavy compression spring 36, seating at one end against a collar formed on the forward or outer end of the guide bar, and at its other end against a boss formed on the extension wall 5, of the casting, thus resisting inward movement of the guide bar. Apertures or recesses 37, may be provided in the rear wall 7, of the main casting, to afford clearance for the rear ends of the guide bars 34, when the same are thrust inwardly their maximum amount. As clearly shown, a peripheral flange 38, is formed on the outer end of the member 15, to limit the inward movement thereof, and

side flanges 39, are also formed thereon acting to limit the outward movement thereof by contact with the guide elements 12.

The operation is as follows:

The various coiled springs, to-wit 27 and 36, co-act with one another and with the resilient friction plates 16, to absorb impacts imparted to the gear due to contact of other objects, such as cars or buffer blocks, with the forward buffer plate 24. Due to the pivotal connection of said buffer plate 24, with the guide bars 34, and the non-rigid central connection thereof, to-wit the spring 27, a deformation of the gear may take place to compensate for impact stresses imposed thereon on one side or the other of the central axis of the gear. In the absorption of the stresses the coiled springs first act to resist movement of the buffer plate 24, being compressed due to rearward movement thereof, and subsequently if the impact is sufficiently great, the resilient friction plates 16, come into action and are deformed between the convex head 14, and the concave seat 17, resisting such deformation, of course, mainly by their friction, and also due to their resilience. Of course in this event, the member 14-15, must first have moved rearwardly, and the inward movement thereof is of course limited by its peripheral flange 38. Although the plates 16, due to the friction therebetween, act practically without recoil, and again assume normal position gradually when the impact stress has been dissipated or removed, the outward movement of the member 14-15, is limited by the side flanges 39, engaging the inner end of the guide plate 12.

I am aware that various details of construction may be varied through a wide range without departing from the principles of this invention, and I therefore do not propose limiting the patent granted otherwise than necessitated by the prior art.

I claim as my invention:

1. A buffing gear of the class described comprising a casting, a top wall and a bottom wall integrally formed thereon, parallel retaining ribs integrally formed on said walls, guide elements removably secured to said walls abutting said ribs, an abutment member movably mounted within said casting between said guide elements, means on said abutment member adapted to contact the guide elements to limit the inward and outward movement of said abutment member, buffer means movably associated with said casting, and resilient means disposed between said abutment member, said casting and said buffer means acting to resist inward movement of said buffer means and said abutment member.

2. In a buffing gear of the class described, a casing, a buffer element slidably engaging the same, retaining ribs integrally formed

in said casing, guide elements removably secured in said casing abutting said retaining ribs, an abutment member movably engaged between said guide elements, a peripheral flange integrally formed on the outer end thereof to limit the inward movement thereof, side flanges integrally formed on said abutment member intermediate the ends to limit the outward movement thereof, a head integrally formed on said abutment member, and resilient means disposed on each side thereof adapted to resist inward movement of said buffer member and said abutment member.

3. In a buffering gear of the class described, a casing, retaining ribs formed therein, guides removably secured within said casing abutting said ribs, a movable buffer member associated with said casing, a movable casing mounted within said casing between said guides, resilient means seated therein and bearing against said buffer member to resist the inward movement thereof, means integrally formed on said movable casing adapted to contact said guides to limit the movement of said movable casing, and means mounted between said casings acting to resist inward movement of said movable casing.

4. In a device of the class described, a casing, a buffer member slidably engaged thereon, means guiding said buffer member and having pivotal connection therewith, a plurality of resilient means disposed at the ends and centrally of said buffer member co-acting to resist inward movement thereof with respect to the casing, ribs integrally formed in said casing, guides removably secured in said casing abutting said ribs, a movable member within the casing affording a seat for said centrally disposed resilient means, resilient mechanisms in said casing, a flange at one end of said movable member, flanges centrally disposed on said movable member, said flanges adapted to abut said guides to limit the movement of said movable member, and a convex abutment head on the other end of said movable member adapted to contact said resilient mechanisms to resist inward movement of said movable member.

In testimony whereof I have hereunto subscribed my name in the presence of two subscribing witnesses.

ARTHUR C. DAVIDSON.
